GOLF PUTTER HEAD

Edward V. Comitz, 4635 E. San Carlos Place,
Tucson, Ariz. 85716

Filed Apr. 7, 1967, Ser. No. 6,576

Term of patent 14 years

(Cl. D34—5)

FIG. 4.

FIG. 2.

FIG. 3.

FIG. 1.

I claim:

The ornamental design for a golf putter head, substantially as shown and described.
